STOCKING PROTECTOR

Herman H. Rowland, New York, N. Y.

Application March 21, 1933, Serial No. 661,913

3 Claims. (Cl. 36—55)

My present invention relates to footwear and more particularly to an improved stocking protector for use in footwear and the like.

In footwear, various improvements have been made to cause the same to more closely fit the shoe of the wearer, not only to insure comfort in use, but also to eliminate relative movement between the foot of the wearer and the shoe structure in order to reduce to as great a degree as possible the wear on socks and stockings incident to such relative movement. Regardless of how carefully the shoe is constructed, it has been impossible to so construct the shoe as to fit the foot and have an entire absence of relative movement between the shoe and the foot of the wearer.

The greatest movement between the foot of the wearer and the shoe structure occurs at the heel of the shoe, and the incessant chafing between the foot of the wearer and the shoe results in the rapid wearing of the heels of the stockings. This is particularly true with regard to present day light weight stockings worn particularly by women, although such wearing of the heel of the stocking is not by any means confined to women. With very light weight stockings it is practically impossible to darn or otherwise repair the same and having anything other than an ill-looking stocking. Consequently, the wearing of a hole in the stocking necessitates the permanent discarding of the stocking with the result that a considerable portion of the cost of clothing is in the item of stockings, particularly with regard to women.

In my present invention, I have devised an improved device for preventing not only the chafing effect on the heels of a stocking but also a device which will to a certain degree correct the tendency on the part of stockings to move to one side or the other of the heel of the wearer.

My device consists of a separate piece of material which is secured to the inner face of the rear portion of the shoe structure and which when in normal position houses entirely within the outline of the shoe and the same is not visible when relative movement between the shoe of the wearer and the shoe structure takes place.

The material of which my device is composed may be anything desired as fabric, rubberized fabric, leather, or any other suitable wear resisting material.

An object of my invention, therefore, is an improved stocking protector for boots, shoes and the like.

An object of my invention is an improved relatively movable guard for interposition between the heel of a stocking and a shoe structure.

An object of my invention is an improved device for assisting in maintaining a stocking in proper position on the foot of the wearer.

Other objects and novel features of the device will appear as the description of the invention progresses.

Fig. 1 is a front view of a length of flat tubular material from which a plurality of protectors embodying my invention may be cut;

Fig. 2 is an end view of Fig. 1;

Fig. 3 is an elevation of one of my improved protectors as cut from the material shown in Fig. 1, and

Fig. 4 is a sectional elevation through a rear portion of a shoe and showing an improved protector embodying my invention in position therein.

Referring to Figures 1 to 4 inclusive, 46 designates a flat tubular structure of any desired material, such as rubberized fabric, leather, artificial leather, the height of such tubular member, as viewed in Figs. 1 and 2, being ordinarily slightly less than the depth of the heel portion 47 of a shoe structure 48.

Referring to Fig. 3, there is shown a structure embodying this latest modification of my invention and it will be noted that such structure is of an inverted truncated cone shape in elevation and I have designated such element by the reference numeral 49. A plurality of such elements 49 may be cut from the flat tubular material 46 by any suitable means as in a cutting die, and it will be noted that the only waste in the use of such material is the substantially triangular sections 50 at the ends of the flat tubular material 46. After being cut from the material 46, the members 49, which are the members

that embody this modification of my invention, are preferably though not necessarily, provided across one face with a band 51 of adhesive, such band being removed from the upper and lower limits of the member 49, and by suitably manipulating the adhesive 51, the member 49 is placed in operative position within the heel portion 47 of the shoe structure 48, and it will be noted that the proper position as indicated in Fig. 4 requires

that the upper roll edge of the member 49 is normally slightly below the upper open edge of the heel 47 and that the lower roll edge of the member 49 is slightly above the bottom of the heel portion 47.

I prefer to use adhesive, although it is obvious

that any other form of device or material of fastening the member 49 in place within the shoe structure 48 may be employed without departing from the spirit of the invention.

5 Further, ordinarily, the material of which the flat tubular member 46 is composed allows the forward side of the members 49, that is the left hand member as viewed in Fig. 4, to be moved upward and downward with respect to the rear side, that is the side to which is attached the adhesive 51, and that in such movement the minimum amount of friction is developed. Therefore, the heel of the wearer will adhere to the front side of the member 49 and any limited movement between the heel of the wearer and the shoe structure 48 will not be communicated to the heel of the wearer as that portion of the devices 49 in contact with the heel is of course stationary as regards the heel of the wearer.

10 20 In order to increase the tendency of slippage between the inner faces of the member 49, I may utilize any lubricant, as for example, talcum powder. In this form of my invention, the portion to which the adhesive 51 has been applied acts when the device 49 is in position in the heel 47 of the shoe structure 48 as a limiting means to limit the upward and downward movement of the heel of the wearer and prevents the accidental casting of the shoe structure 48 as may 15 sometimes happen.

25 30 Various other forms of my invention will readily suggest themselves to those skilled in the art and I do not, therefore, limit myself to the exact construction shown, the main feature of my invention residing in a device having one end attached to or formed integral with a shoe structure and having a roll or fold therein to connect the same to the main portion of the device, and which main portion is in engagement with 35 and practically immovable as regards the foot 40 of the wearer, and having relative sliding move-

ment with regard to the shoe structure and wherein the roll or fold travels along the length of the body of the device as relative movement takes place between the foot of the wearer and the shoe structure.

5

I claim:

1. A stocking protector comprising a substantially flat tubular member of flexible material having rearward and forward portions arranged parallel to and in sliding engagement with each other, and adhesive means on the rearward face of the rearward portion, the area of the adhesive being less than the area of the engaging faces of the forward and rearward portions, whereby the sliding movement of the forward portion on the rearward portion is limited by the extent of area of the adhesive.

2. A stocking protector comprising a substantially flat tubular member of flexible resilient material having rearward and forward portions arranged parallel to, and in practical sliding engagement with each other, said forward portion being adapted to engage with the heel of a wearer; adhesive means on the rearward portion for attaching the tubular member to the heel of a shoe, the limit of sliding movement of the forward portion with respect to the rearward portion being limited by the adhesive.

3. A stocking protector comprising a structure having the form of an inverted frustum of a cone in front elevation and composed of flexible and substantially inextensible material in the form of a closed flat loop and with the folds of the loop in sliding engagement with each other, and adhesive on the rearward fold of the loop for attachment to the heel of a shoe, the area of the adhesive being less than the area of the engaging folds of the loop, whereby the limit of sliding movement of the folds with respect to each other is controlled by the adhesive.

40 HERMAN H. ROWLAND.
